UNITED STATES PATENT OFFICE.

WILLIAM H. BURK, OF CHATTANOOGA, TENNESSEE, ASSIGNOR TO NANNIE BURK, OF CHATTANOOGA, TENNESSEE.

INTERNAL-COMBUSTION ENGINE.

1,250,135.

Specification of Letters Patent. Patented Dec. 18, 1917.

Application filed July 13, 1916. Serial No. 109,127.

To all whom it may concern:

Be it known that I, WILLIAM H. BURK, a citizen of the United States, residing at Chattanooga, in the county of Hamilton and State of Tennessee, have invented certain new and useful Improvements in Internal-Combustion Engines, of which the following is a specification, reference being had therein to the accompanying drawing.

10 This invention relates to internal combustion engines.

The invention is directed to means for introducing a liquid, in the form of steam or other vapor, into the gaseous mixture flowing into the internal combustion engine, whereby carbonizing of the interior of engine cylinder may be eliminated.

One of its objects is to provide, in conjunction with such means, an instrumentality controlled by the condition of the engine, whereby the amount of vapor so introduced may be automatically regulated in accordance with certain predetermined requirements of the engine to which it is attached.

25 Another object of the invention is the provision of means whereby the vapor which is to be introduced to the engine cylinder may be superheated before its introduction.

Other objects and advantages will in part 30 be apparent and in part brought out in the description which follows:

Drawings illustrating a preferred embodiment of the invention are hereto appended, in which:—

35 Figure 1 is a diagrammatic view in elevation showing an application of the invention to an internal combustion engine;

Fig. 2 is a side elevation of a form of vaporizing apparatus; and

40 Fig. 3 is a vertical sectional view of the same.

Referring specifically to the drawings, the numeral 1 designates generally an internal combustion engine. It comprises cylinders 2, a carbureter 3, an intake manifold 4 connecting said cylinder and carbureter, and an exhaust manifold 5.

In conjunction with this engine, my invention provides a liquid tank 6, a vaporizer 7 comprising a casing, having an air opening 8, a liquid receiving opening 9, and a vapor exhaust opening 10. Connecting the liquid tank 3 and the liquid receiving open-

ing 9, there is a pipe 11 and in this pipe there is a valve 12.

55 Suitably secured to the casting of the vaporizer there is a stem 13, adapted to be threaded into the exhaust manifold. This stem is hollowed out on its exterior and is preferably placed in alinement with the liquid receiving opening of the casing, the object being to receive heat from the products of combustion which pass through the exhaust manifold and communicate this heat to the interior of the hollow portion of the 65 tube to vaporize the incoming liquid.

Means are provided for automatically regulating the amount of vapor to be introduced to the engine cylinder, by effecting the regulation of the amount of liquid introduced to the engine.

To this end, a thermostat 14 is inclosed in the tubing and has its lower portion resting on the bottom thereof. Its upper portion is in engagement with a link 15 secured at one end to a standard 16 disposed within the casing, the other end of the link being in connection as through a rod 17 with a valve 18 disposed in the liquid inlet opening. Normally the liquid enters the casing very slowly and is almost 80 immediately vaporized. The thermostat being in the direct passage of the liquid which enters the casing, it will be seen that if too much liquid enters the casing the rod will be cooled thus contracting. This contraction of the rod will be communicated through the links just described to the valve to close the liquid inlet.

85 The heating of the thermostat will have the opposite effect, namely to expand the rod which in turn will open the liquid inlet valve permitting more liquid to enter the casing and become vaporized.

For the purpose of superheating the vapors thus generated a pipe of the like 19 95 is carried from the vapor outlet opening in the casing and formed into a heating coil 20, wound around the exhaust manifold from whence it is carried to the carbureter.

In order to permit the withdrawal of the 100 vapor from the casing due to the vacuum created in the engine cylinder, there is provided a valve 21, in the air vent in the casing.

From the foregoing, it will be apparent that my invention provides simple and effective means for producing the results above 105

stated as desirable, and while I have disclosed it in the embodiment herein shown it will be understood that many changes in the construction and general arrangement will be within the scope of the invention.

What I claim is:

1. A device for introducing vapor to an internal combustion engine having a cylinder and an exhaust therefrom, said device comprising a vapor generator; means for introducing vapor to the cylinder; and automatic means including a thermostat governed by the temperature of the exhaust, for regulating the production of vapor.
2. A device for introducing vapor to an internal combustion engine having a cylinder and an exhaust therefrom, said device comprising a vapor generator; means for introducing vapor to the cylinder; and automatic means including a thermostat governed by the temperature of the exhaust, for regulating the introduction of vapor to the cylinder.
3. A device for introducing vapor to an internal combustion engine having a cylinder and an exhaust therefrom, said device comprising a vapor generator; means for supplying liquid to the generator; means for introducing vapor to the cylinder; and automatic means including a thermostat governed by the temperature of the exhaust for regulating the amount of liquid supplied to the generator.
4. A device for introducing vapor to an internal combustion engine having a cylinder, said device comprising a vapor generating instrumentality, means establishing a communication between said generator and said cylinder; said vapor generating instrumentality comprising a casing having a liquid inlet and a vapor outlet, a valve mechanism in said liquid inlet and means comprising a thermostat for controlling said valve.
5. A device for introducing vapor to an internal combustion engine having a cylinder, said device comprising a vapor generating instrumentality, means establishing a communication between said generator and said cylinder; said vapor generating instrumentality comprising a casing having a liquid inlet and a vapor outlet, a valve mechanism in said liquid inlet, means comprising a thermostat for controlling said valve, and means for superheating the vapor for introducing it to the cylinder.
6. A device for introducing vapor to an internal combustion engine having a cylinder, said device comprising a vapor generating instrumentality, means establishing a communication between said generator and said cylinder; said vapor generating instrumentality comprising a casing having an air inlet, a liquid inlet and a vapor outlet, a

valve mechanism in said liquid inlet, and means comprising a thermostat for controlling said valve.

7. A device for introducing vapor to gaseous mixtures for use in internal combustion engines having a cylinder, an intake and exhaust manifolds respectively; said device comprising a casing having a hollow stem 70 adapted to be threaded into the exhaust manifold and having also a liquid inlet, an air inlet and a vapor outlet passage respectively; a valve mounted in said liquid inlet; a valve actuating member secured thereto; a link pivotally mounted at one end on the interior of said casing and connected at its other end to said valve actuating member; a thermostat disposed in said hollow stem and connected at its opposite end with said link; means establishing communication between said vapor outlet, and said cylinder, said means being carried around the exhaust manifold; a source of liquid supply; and means establishing communication between 25 said source of liquid supply and said liquid inlet.

8. A device for introducing vapor into fuel for an internal combustion engine having an exhaust passage and a fuel passage, 90 said device comprising a liquid tank; a vaporizing member associated with the exhaust passage and having a casing provided with an air vent, with an inlet for the liquid to be vaporized and with an outlet for the vapor, means connecting the tank and the liquid inlet; means connecting the vapor inlet and fuel passage of the engine, automatic means for regulating the feeding of liquids to the vaporizer, comprising a thermostat 100 disposed within the vaporizer casing and influenced directly by the amount of liquid being fed to the vaporizer.

9. A device for introducing vapor into fuel for an internal combustion engine having an inlet and exhaust passage, said device comprising a liquid reservoir; a vaporizer including a casing provided with an air vent, with a liquid inlet, with a vapor outlet, and having secured to said casing a hollow heating member adapted to be threaded into an exhaust passage of the engine; a connection between the liquid reservoir and the liquid inlet of the casing; a pipe connecting the vapor outlet and a fuel inlet of the engine, said pipe passing around an exhaust passage of the engine, whereby the vapor may be heated before being introduced to the fuel; and automatic means for regulating the amount of liquid being fed to the vaporizer, comprising a thermostat mounted within the hollow heating member.

In testimony whereof I affix my signature.

WILLIAM H. BUR
